UNITED STATES PATENT OFFICE.

ALLAN E. JOHNSON, OF MONTREAL, QUEBEC, CANADA.

BOX-CAR UNLOADER.

1,420,431.

Specification of Letters Patent. Patented June 20, 1922.

Application filed May 18, 1920. Serial No. 382,245.

To all whom it may concern:

Be it known that I, ALLAN E. JOHNSON, of the city of Montreal, Province of Quebec, Dominion of Canada, a subject of the King 5 of Great Britain, have invented certain new and useful Improvements in Box-Car Unloaders; and I do hereby declare that the following is a full, clear, and exact description thereof.

10 My invention relates particularly to the means for facilitating the discharge of loose commodities such as grain, sand, lime, coal, gravel and the like from box cars, and it is for use particularly in conjunction with 15 means for tilting the car; the object of the invention is to provide a baffle which will be caused by automatic action to enter the car and assume a position which will in co- 20 action with the tilting of the car secure the effective discharge of the lading, and when not in use be clear of the space in front of the door. Baffles for co-acting with the tilting mechanism in box car unloaders are well known and the defects of bad fitting of the 25 parts and obstruction of the space before the door in these baffles and other operating mechanism at present in use are sought to be overcome by my invention. To this end my invention consists of a baffle with means 30 for inserting and withdrawing the same through the side door of a car and adapted to hold up the baffle until it gets into the car and then cause it to subside until it rests on the floor along which it is projected until it comes into contact with the opposite 35 side of the car, one side door only of which is open. Co-acting with the means for inserting and elevating and lowering the baffle is means for sluing the baffle round to a position at one side of the door opening when 40 fully withdrawn from the car.

For full comprehension, however, of my invention, reference must be had to the accompanying drawings in which similar reference characters indicate the same parts, and wherein:

Figure 1 is a plan view of one of my improved baffles and supporting structure;

Figure 2 is a side elevation thereof;

50 Figure 3 is a vertical sectional view taken on line 3—3 Figure 2;

Figure 4 is a plan view of a car and my improved baffle mechanism with one of the baffles in position for discharging; and

55 Figure 5 is a horizontal sectional view taken on line 5—5 Figure 3.

The baffles which are adapted to be inserted obliquely through the door opening and act as deflectors for discharging lading and the mechanisms for actuating them are 60 located on and at one side of the platform supporting the car on opposite sides of the door opening. The baffles indicated at 2 and 3 with their actuating mechanisms are similar in all respects except that each baffle consists of a pair of sheet metal plates 4 mounted upon interposed channel irons 5, (the lower edge of the portion adapted to be inserted within the car having a flexible strip 6 secured thereto.) The fixed supporting 70 structure for each baffle constitutes a part of the frame 7 and includes top and bottom guideways 8 and 9. The extreme outer end of the baffle is slidably supported by collars 10 upon a vertical shaft 12 the upper end of 75 which carries a roller 13 travelling in the guideway 8 while the lower end is mounted on a carriage 14 running on a roller 15. The latter is located midway the length of the carriage to permit the latter to rock thereon 80 and consequently adjust itself to the inclination of the baffle. Rollers 16 rotating on vertical axes are located at opposite ends of the carriage and are adapted to contact with the sides of the guideways. 85

Adjacent to the track are additional supports for the baffles. They are formed by the upper and lower guiding brackets 17 and 18 pivotally mounted on a vertical shaft 19 located in position in the frame 7 adjacent 90 the car and to one side of the door opening thereof. These brackets are constructed and arranged to straddle the upper and lower side edges of the baffle. The upper bracket is slidably mounted upon the shaft and has 95 vertical rollers 20 adapted to bear against the sides of the baffle while the lower bracket is also provided with vertical rollers 21 performing a similar function and a roller 22 mounted on a horizontal axis and bearing 100 against the bottom edge of the baffle. This lower bracket is integral with collar 23 and sleeve 24 which encircles the shaft 19 and is fixed longitudinally in position on the shaft by retaining collars 25. Straddling 105 sleeve 24, and bearing on the lower surface of the collar 23, is the forked end 27 of a lever 28, bearing an adjustable counterweight 29 and fulcrumed as at 30 adjacent the said forked end in a standard 31 constituting a 110 part of the frame 7. The purpose of this counterweight is to increase the bearing of

the front end of the baffle on the car floor, as it approaches its fully inserted position in the car, by supporting the weight of shaft 19 and its attached parts, and enough of the weight of the baffle to reduce its bearing at adjacent edge of car floor to a small amount, after the partial support for these parts, by nut 42, has been withdrawn as hereinafter explained.

10 The mechanism for actuating each baffle consists of the shaft 19 hereinbefore referred to, a drum 32 mounted thereon and keyed thereto, a rope 33 wound on the drum with its opposite ends connected to the front end of the baffle as at 34 and to the rear end of the baffle as at 35 and a motor 36 adapted to drive the shaft 19 through a worm 37 in intermeshing relation with the worm wheel 38, the worm wheel having a squared opening 39 receiving the squared upper end of the shaft 19 and permitting the latter to move axially relatively to the worm wheel. The lower end of the shaft 19 is contained within a housing 40 having a reduced opening at its lower end, to present a shoulder 41 adapted to limit downward movement of a nut 42 mounted upon the threaded lower end of the shaft 19. Integral with nut 42 is a square collar 43, adapted to slide vertically within a square prismatic portion of the housing which prevents its turning.

The portion of the frame adjacent the door opening carries a metal wall 45 bearing a door 46 for sealing the opening through which the baffle passes, being curved to enable the baffle to push it open as it moves towards the car.

40 A limiting switch 47 is mounted upon the frame 7 adjacent the rear of the baffle and is adapted to be engaged by a projection 48 on the carriage 14 for the purpose of limiting outward movement of the baffle by stopping the motor.

45 In the operation of my improved baffle mechanism after the door of the car has been forced open, the motor 36 is set in motion and the shaft 39 rotated thereby winding the rope 33 on the drum 34 and pulling the baffle into the car at the angle thereto illustrated in Figure 4. It is essential that the front end of the baffle clear the highest door sill of any car to be used and consequently this end of the baffle when it commences its travel must be located at a high enough level 50 to accomplish this and as the baffle is fed in across the car it is necessary that it should be lowered into contact with the floor of the car in order that the grain may not pass underneath to the opposite end of the car. 55 This lowering motion is obtained by the shaft 19 and nut 42, the shaft being, as hereinbefore stated, capable of axial movement, initial rotation of the shaft allowing the latter to feed downwardly through the nut 60 which is seated upon the shoulder 41 until

the baffle has entered the car and come into contact with the floor of the car, by which it is partially supported during the remainder of its inward movement. Continuous rotation of the shaft causes the nut 42 to rise 70 in housing 40 when not required for assisting in supporting shaft 19 and attached parts.

The counterweighted lever is adapted to assist in supporting the outer end of the 75 baffle for the purpose of increasing the tendency of the forward portion thereof to swing down into a continuous bearing upon the floor as the shaft is lowering the baffle. In withdrawing the baffle from the 80 car the reverse operation takes place.

The baffles and all their operating mechanisms are rigidly connected to the main frame or cradle which carries the car, and that they maintain their relative position 85 with respect to the car during all its movements during the dumping process, and that the operations of the baffles may be carried on simultaneously with the tilting of the main platform, or cradle.

90 In withdrawing the baffles they first move in substantially their own plane but as they reach such a position that movement, transversely to their own planes, will not be much interfered with by the material to be 95 unloaded, either in withdrawing or reinserting, their outer ends are caused to move approximately parallel to the longitudinal central plane of the car, thus reducing their maximum distance from this plane. This 100 movement is secured by the angular shape of the guides 8 and 9.

95 What I claim is as follows:

1. The combination with a baffle for insertion into a box car for the purpose set forth, of means for inserting and withdrawing such baffle and means for successively raising and lowering the baffle relatively to the car floor while being inserted and raising and lowering the same relatively to the 110 car floor while being withdrawn.

2. The combination with a tiltable support for a car and a baffle for insertion into the car for the purpose set forth, of means for inserting and withdrawing such baffle 115 and means for successively raising and lowering the baffle relatively to the car floor while being inserted and raising and lowering the baffle relatively to the car floor while being withdrawn, and means for sluing 120 round the baffle to a position substantially parallel to the car support.

3. The combination with a tiltable support for a car and a baffle for insertion into the car for the purpose set forth, of means 125 for inserting and withdrawing such baffle and means for successively raising and lowering the baffle relatively to the car floor while being inserted and raising and lowering the baffle while being withdrawn, and means 130

- for sluing round the baffle to a position substantially parallel to the car support while being withdrawn.
4. The combination with a baffle for insertion into a box car for the purpose set forth, of means for inserting and withdrawing the baffle into and from the car, and means for lowering and raising the baffle relatively to the car.
5. The combination with a baffle for insertion into a box car for the purpose set forth, said baffle being disposed in a position substantially parallel to the car, means for inserting and withdrawing the baffle into and from the car, and means for sluing round the baffle to position transversely to the length of the car as it is inserted and for sluing it round to position substantially parallel to the car as it is withdrawn.
6. In a baffle mechanism of the type described top and bottom guideways, and a baffle slidably mounted therein, said guideways being of angular form one side of the angle extending substantially parallel to the car and the other side of the angle at an angle thereto for the purpose of sluing round the baffle as it is inserted and withdrawn from the car.
7. The combination with a baffle for insertion into a box car for the purpose set forth of means for inserting and withdrawing such baffle, said means consisting of a shaft a drum upon the shaft a rope wound upon the drums and having its ends connected to the opposite ends of the baffle, and means for rotating said shaft, and means for causing axial movement of the shaft for the purpose of lowering and raising the baffle relatively to the car.
8. The combination with a baffle for insertion into a box car for the purpose set forth of means for inserting and withdrawing such baffle, said means consisting of a shaft a drum upon the shaft a rope wound upon the drums and having its ends connected to the opposite ends of the baffle, and means for rotating said shaft, and means for causing axial movement of the shaft for the purpose of lowering and raising the baffle relatively to the car, said last mentioned means consisting of a nut screwed upon the said shaft and held against rotation, and means constructed and arranged to limit axial movement of said nut.
9. The combination with a baffle supporting structure and a baffle slidably mounted in said structure for insertion into a box car for the purpose set forth, of means for inserting and withdrawing said baffle, and means for supporting the outer end of the baffle as it is inserted into the car for the purpose of increasing the tendency of the inner portion of the baffle to bear upon the car floor.
10. The combination with a baffle sup-
- porting structure and a baffle slidably mounted in said structure for insertion into a box car for the purpose set forth, of means for inserting and withdrawing said baffle, and means for supporting the outer end of the baffle as it is inserted into the car for the purpose of increasing the tendency of the inner portion of the baffle to bear upon the car floor, said last mentioned means consisting of a member bearing upon the lower edge of the baffle, a lever fulcrumed in the supporting frame adjacent one end with such end in bearing relation with the member bearing upon the lower edge of the baffle and a counterweight located on the opposite end of said lever.
11. The combination with a tiltable support for a car of baffle mechanism mounted upon said support and tiltable therewith, said mechanism consisting of a pair of baffles and located at one side of the car and on each side of the door opening, means for inserting and withdrawing each of said baffles into and from the car, and means for guiding each baffle in its movement whereby it assumes a position substantially parallel to the car when in its outermost position and assumes a position transversely to the car when in position therein.
12. In a baffle mechanism for unloading box cars the combination with a supporting structure presenting top and bottom guideways, a carriage movable within said guideways, a baffle having its outer end mounted upon said carriage, a shaft located at the end of said guideways adjacent the car, a bracket mounted upon said shaft, and supporting the baffle, a drum mounted upon said shaft and rotatable in unison therewith, a rope wound around said drum with its ends connected to the opposite ends of said baffle, a motor for rotating said shaft, means for causing axial movement of said shaft for the purpose of moving the baffle relatively to the car floor, said means consisting of a nut screwed upon the shaft and held against rotation and a stop intersecting path of the nut and adapted to limit axial movement thereby.
13. In a baffle mechanism for unloading box cars the combination with a supporting structure presenting top and bottom guideways, a carriage movable within said guideways, a baffle having its outer end mounted upon said carriage, a shaft located at the end of said guideways adjacent the car, a bracket mounted upon said shaft, and supporting the baffle, a drum mounted upon said shaft and rotatable in unison therewith, a rope wound around said drum with its ends connected to the opposite ends of said baffle, a motor for rotating said shaft, means for causing axial movement of said shaft for the purpose of moving the baffle relatively to the car floor, said means consisting

of a nut screwed upon the shaft and held against rotation and a stop intersecting path of the nut and adapted to limit axial movement thereby, means for increasing the 5 tendency of the inner end of the baffle to bear upon the car floor as it is inserted, said means consisting of a lever fulcrumed adjacent one end such end being forked and straddling and in operative engagement with 10 said bracket and a counterweight mounted upon the opposite end of said lever.

14. In a baffle mechanism for unloading box cars the combination with a supporting structure, a baffle slidably mounted in said structure, of means for inserting and withdrawing said baffle into and from a car, said means including a motor and means for automatically stopping the motor when the baffle has reached its outermost position said 20 means consisting of a switch mounted upon a supporting structure and a device movable with the baffle in a path intersected by said switch.

15. In a baffle mechanism for unloading

box cars the combination with a supporting 25 structure including a wall adjacent the door opening of the car, said wall having an opening therein a baffle slidably mounted in said structure and movable through said opening in the wall when being inserted and 30 withdrawn from the car and a door for closing said opening and constructed and arranged to be swung open by the baffle, said door being of curved cross-section, means for yieldingly maintaining said door in closed 35 position and for maintaining it in bearing relation with the adjacent side of the baffle when open for the purpose of preventing the discharged lading passing through the opening. 40

In testimony whereof I have signed my name to this specification in the presence of two witnesses.

ALLAN E. JOHNSON.
